UNITED STATES PATENT OFFICE.

ADOLF FRANKE, OF GRUNEWALD, NEAR BERLIN, GERMANY, ASSIGNEE TO SIEMENS & HALSKE, A. G., OF BERLIN, GERMANY, A CORPORATION OF GERMANY.

TELEPHONE SYSTEM.

1,268,106.

Specification of Letters Patent.

Patented June 4, 1918.

Application filed September 3, 1913. Serial No. 787,912.

To all whom it may concern:

Be it known that I, ADOLF FRANKE, a German citizen, and resident of Grunewald, near Berlin, Germany, have invented certain new and useful Improvements in Telephone Systems, of which the following is a specification.

This invention relates to automatic telephone systems in which connections are established by means of selectors and in which in case of larger plants it is customary to divide the subscribers into main groups (tenths of thousands), and sub-groups (thousandths, hundredths, etc.) and to adjust a first selector (I. group selector) upon the desired main group, thereupon a second selector (II. group selector) upon the desired sub-group and finally further selectors upon the desired line. This adjustment has the disadvantage that the so-called group selectors remain engaged during the entire duration of the conversation. It has therefore been proposed to establish a connection of the found desired place with the calling station upon a shorter path after completion of the directed selection with the group selectors. For this purpose between each two subscriber groups circumventing connections have been provided, said circumventing connections including switching apparatus for making the connection for talking over this shorter and cheaper way in case such circumventing line be excited from either side, while the directing selectors are rendered free. This arrangement, however, has the disadvantage that the number of the circumventing ways will increase about proportionally to the square of the places to be connected.

The object of my invention is to provide a mode of connecting, in which the aforesaid disadvantage is obviated by having the auxiliary connection made between a calling station and a desired station by selecting the direction substituted by a circumventing connection which is made up of several parts according to free or directed selection. In this case for connections between different groups always several portions are joined.

A connection of this kind will be especially valuable if the calling station is connected in the ordinary manner first with a point of a multiple field, whereby the number of these points is essentially smaller than that of the calling stations. To give an ex-

ample, by double pre-selecting the service of 2,000 subscribers may be reduced to 100 connecting points at a multiple field. According to this invention the directed selection of the auxiliary connections will begin at this multiple field and the selectors of the circumventing connection will then only need to seek one of 100 points instead of one of 2,000 points. Also the desired subscribers are advantageously switched upon such a multiple field, whereby the same pre-selectors or call seekers may be used as in case of a call of the respective subscriber. For the aforesaid second selection then only a simple bridging of a branching point of the one or the other multiple field will have to be accomplished. The number of these branching points can be very small as compared with the number of subscribers, as these branching points are common for large subscriber groups (about 2,000 subscribers) and need to be provided only in such a number corresponding to the percentage required by the demand. Accordingly, also the number of the combinations of connections for the second selection will be reduced to an essential smaller value such as is customary in case of exclusive forward selecting (for instance according to the Strowger system). The bridging may therefore be done with a few selectors. The number of selectors, however, may further be reduced independently therefrom by employing selectors with a larger multiple field.

The bridging of the two multiple fields may be accomplished by forward or back selecting, as desired. In either case this bridging will be effected automatically by a numeral sender associated with the branching point sought by the second selection, and which by reason of this latter relation is so connected that it will immediately furnish the current impulses which are required in each case and pass said impulses over auxiliary connection to the second selectors to be adjusted.

My invention will be more fully understood by reference to the accompanying drawings of which Figure 1 shows multiple fields for switching the calling subscriber by means of double pre-selecting, Fig. 2 a telephone system similar to that of Fig. 1 in which a multiple field is provided back of the first group selector, Fig. 3 a subscriber

station with relaying accessories, call seeker and pre-selector, Fig. 4 a connection containing the set of relays of a multiple field contact of the calling end, Fig. 5 a seeker in connection with a numeral sender and first group selector, Fig. 6 a second group selector, Fig. 7 a line selector, Fig. 8 a subscriber station II with call seeker and pre-selector and Fig. 9 an arrangement containing the set of relays of a multiple field contact of the called end including a back-selector.

Referring now more particularly to the drawings I have shown multiple fields A and B upon which the calling subscriber I or the called subscriber II may be connected by double pre-selecting, that is to say, by means of a call seeker and a pre-selector, the auxiliary connection being shown by a dotted line. This auxiliary connection leads in the manner as usual in the Strowger system over an I. and II. group selector and a line selector which latter will excite a free call seeker and pre-selector, whereby the line of the desired subscriber will be switched upon a branching point of the multiple field B. The final connection of the branching points engaged at the multiple field A or B will be done automatically in that the numeral sender ZG will send current impulses over the group selectors and the line selector to the so-called back selector RW. After adjustment of this selector the auxiliary connection which is shown in dotted lines will be made inoperative. Before the I. group selector a seeker S is inserted in order to be able to switch the group selectors which are being used only for a relatively short time during the call, upon a larger number of branching points. In case of large telephone systems I have devised an arrangement which is shown in Fig. 2. In this arrangement a group selector is employed for auxiliary as well as for final selecting.

In order to make a connection between the subscribers I and II, now, the following operations will be made:

After taking off the receiver at I the call seeker AS¹ together with the pre-selector VW¹ will adjust themselves, the call seeker apparatus upon the calling subscriber line, the pre-selector upon the line of the free multiple field contact of Fig. 4. After adjustment of both apparatus the subscriber will be connected with the set of relays of Fig. 4. Immediately therewith the adjustment of the seeker S in Fig. 5 will take place, whereby the subscriber I will be connected with the I. group selector. Call seeker, pre-selector and seeker are supposed to be plain rotary selectors which work in steps.

Now, the subscriber will select the desired multiple field II by means of its dial switch. In the system represented I have assumed call numbers having four digits. Thus, the

disk will have to be set, accordingly. Thereby the I. and II. group selector and the line selector will be adjusted in succession, said selectors being constructed for lift and rotation similar to those of the Strowger type. Upon the first rotation of the disk the shaft of the first group selector will be lifted by a corresponding number of steps, whereupon by rotation of the contact arms a free line will be sought automatically. Similarly upon the second rotation of the disk the adjustment of the second group selector will be accomplished, and upon the third and fourth rotation of the disk the line selector will be lifted and rotated respectively and thereby adjusted upon the line of the desired subscriber.

If the line be free the call seeker AS² and pre-selector VW² will immediately be adjusted. Hereby the line of the subscriber II will be connected with a set of relays of the multiple field, whereupon by co-operation of the numeral sender ZG of Fig. 5 the adjustment of the back selector RW upon the interconnecting contact of Fig. 4 will be further accomplished automatically. The connection over the seeker, group selectors and line selector will then immediately be separated, while the talking connection over the back selector will remain as shown by the full drawn lines. From the back selector call signals will be transmitted to the subscriber II and conversation may be taken up as soon as the latter subscriber will answer the call by taking off the receiver. The circuit for talking is divided by means of condensers into two halves with independent feeding for the microphones. If after completion of the conversation the two subscribers will replace the receivers the established connection will be released on the one or other side of the condensers independently from the one or other subscriber.

First—Pre-selecting.

Upon taking off the receiver at the place I the call relay R¹ together with the starting retarding relay A¹ will respond. A¹ switching at 5 the rotating magnets D¹, D² for the call seeker or pre-selector in the circuit of an interrupter 6. Besides A¹ connects the test relays P¹, P² with ground at 7 and 8. The call seeker and after it the pre-selector will rotate. The call seeker now will operate until at the contacting of the calling line a current will excite the test relay P¹, a circuit being formed over ground, 7, P¹, 8, seeker arm, 9, low resistance winding 10 of T¹, battery and ground. P¹ switches at 11 the rotating magnet D¹ of the call seeker out of circuit, whereupon the call seeker will stop its motion. P¹ also closes at 11^a the circuit for the rotary magnet D² of the pre-selector VW¹. The pre-selector will operate independently

herefrom until at the contacting of the line leading to the set of relays of Fig. 4, a current will flow over ground, 8, P², 12, third arm of the pre-selector, VV¹, 13, 14, 5 battery, and ground, whereby the relay P² will be excited. This relay will switch at 15 the rotary magnet D² of the pre-selector out of circuit, whereupon the latter will stop its motion. P² furthermore will make busy 10 the line 13 by short circuiting its high resistance winding at 16. Also the calling subscriber line had been locked against seizure upon responding of T¹ by interruption of the line 17 at the contact 18, said 15 line branching off to the line selector. Furthermore T¹ will switch off the relays R¹ and A¹ at the contacts 1 and 4, respectively. After P¹ and P² being excited, that is to say, 20 after call seeker and pre-selector have both been adjusted, C¹ will respond to a current flowing over ground, 22, 23, C¹, battery and ground. C¹ will extend the line of the subscriber I to a pre-selector and set of relays of Fig. 4 at the contacts 25 and 26 and 25 will disconnect by short-circuiting at 27 the relay P¹. Furthermore C¹ will close a contact 28 parallel to 23, whereby C¹ will be kept further excited independently of P¹. C¹ further opens again the circuit for D¹ 30 and D² at the contact 29.

In Fig. 4 the impulse relay J⁵ which is connected over 30 and 31 with the subscriber I will respond and therewith also the retarding relay V⁵ and starting relay A⁵. 35 Relay V⁵ switches retarding relay V⁶ into circuit at 24, said relay V⁶ opening the contact 14 for the purpose of subsequent release of the call seeker and pre-selector. A⁵ causes the seeker S of Fig. 5 to start by 40 switching the rotary magnet D⁵ into an interrupter circuit at 35. This seeker will operate until it finds the line 37, characterized by the relay V⁷, by closing contact 36. In this case the following testing circuit will 45 be made: ground, P⁷, seeker arm, 37, 36, V⁷, battery and ground. P⁷ switches the rotary magnet D⁸ out of circuit at 38, whereupon the seeker will stop. P⁷ furthermore short-circuits at 39 its test winding, but will 50 further be kept excited by a contact 34 closed by J⁸ over Z⁷ and 40. By the short-circuit of the one winding P⁷ has been made a retarding relay which is important for the operation following. P⁷ has closed at 41 55 a circuit for the impulse relay J⁸, said circuit being made over ground in Fig. 4, 42, 43, seeker, 41, J⁸, switch arm, 44, resistance, battery and ground. As regards the arrangement shown in Fig. 4 it must further 60 be noted that the testing current flowing over line 37 has excited the retarding relay V⁷, whereupon this latter will hold itself over 45, 32 until the end of the conversation while it will switch off the previously excited relays V⁵ and A⁵ in order not to

further affect the seeker S of Fig. 5. V⁷, after V⁵ being deenergized, will further maintain at 46 the current for V⁶ so that the latter relay will be kept excited.

Second—First selecting controlled from the subscriber.

If the subscriber rotates the disk, the current flowing in the line over J⁸ in Fig. 4 will be shortly interrupted one or several 75 times according as to whether he will choose a low or high number, each interruption will cause a falling of the levers of the impulse relay J⁸. J⁸ will transmit the current impulses upon the selectors. The short openings of the contact 32 in Fig. 4 are not detrimental, since the relay V⁷ is being retarded.

Each opening of the contact 42 in Fig. 4 will cause the relay J⁸ to be deenergized. At the first deenergizing the retarding relay V⁸ will respond, and keep its levers continuously attracted during the sending of the impulses. V⁸ closes at 43 a circuit for the control magnet St and at 49 a circuit for the lifting magnet H⁸. The latter receives at each deenergizing of J⁸ a current impulse, lifting the selector arm by one step. After the last current impulse J⁸ will keep its armatures attracted for some longer time causing the falling of the levers of V⁸. 95 With V⁸ also St will be deenergized. St upon the backward motion of the armature switches the control levers 44 and 50—55 from the first upon the second contacts. Hereby lever 51 will insert the rotary magnet D⁸ into the circuit of an interrupter 104. D⁸ rotates the selector arm by steps from one line contact to the other. If the selector arm contacts with the line to the II. group selector of Fig. 6 which is supposed to be 100 free, the test relay P⁸ will respond and interrupt the circuit made during the operation of D⁸ over St at 56. Consequently the control levers will move into the third position. Lever 51 switches D⁸ out of 110 circuit, lever 54 switches P⁸ off and lever 53 makes busy the found line by grounding. Lever 44 switches J⁸ over to the II. group selector, whereupon in the latter the impulse relay J¹¹ and retarding relay 115 V¹¹ will respond, a circuit for V¹¹ being formed over ground, H¹¹, 57, 58, V¹¹, battery and ground. The winding 59 of V¹¹ is of such high resistance that H¹¹ will not respond.

Upon the second rotation of the disk of the subscriber the current flowing over J⁸ and J¹¹ will be shortly interrupted one or several times, causing a circuit for strong impulses to be at each time closed at 60 for 125 the lifting magnet H¹¹ which lifts the selector arm by one step. At the first step the winding 59 will be switched off at 58, V¹¹ will remain excited over its second winding 61 and contact 62 until after the 130

last current impulse when the contact 60 will remain opened for some longer time. The relay V^{11} , which thereupon will fall off under retardation, switches at 62 the lifting magnet H^{11} out of circuit and at 63 the rotary magnet D^{11} into circuit, said latter circuit being formed over ground, interrupter, D^{11} , 63, 64, 65, 66 (being closed at the first lifting step of the selector arm), battery and ground. D^{11} will rotate the switching axle until upon contacting of a line with a supposed free line selector of Fig. 7, the test relay P^{11} will respond and open the circuit for D^{11} at 65. P^{11} will make busy the chosen line by immediate grounding at 67 and will further keep itself excited by insertion of a second winding 68 at 69. P^{11} further will disconnect the impulse relay J^{11} at 94 and switch the circuit leading from Fig. 4 over J^3 over to the line selector in which now the impulse relay J^{12} and the retarding relays V^{12} , V^{13} , V^{14} will respond. V^{12} and V^{13} are switched into circuit by J^{12} at 70 and V^{14} is switched into circuit by V^{12} at 71.

Upon the third rotation of the disk at the subscriber's station, the current flowing over J^8 and J^{12} will be shortly interrupted one or several times causing at each time a current to flow from J^{12} at 72 over the lifting magnet H^{12} . Each current impulse over H^{12} will lift the selector arms by one step. At the first lifting step the contacts 75, 76 will open and 77 will close. The opening at 75 will be first without effect as the excited retarding relay V^{12} keeps a parallel contact 78 in closed condition. The opening at 76 will cause V^{12} to have its lever fall off after the last lifting current impulse and to switch the rotary magnet D^{12} instead of the lifting magnet H^{12} into circuit. Upon the fourth and last rotation of the disk at the subscriber station, therefore, the current impulses will pass over the rotary magnet, ground, 72, 79, 80, 81, D^{12} , battery and ground. Each current impulse over D^{12} will rotate the switching axle by one step. At the first rotating step the winding 82 of V^{12} will be switched off at 83. Consequently after the last current impulse for rotation V^{12} will fall off and switch V^{14} out of circuit at 71. On account of its retardation V^{14} will fall off somewhat later than V^{12} . In the meantime the desired subscriber line upon which the selector is now adjusted will be tested.

If the line be free a test current will flow over a circuit formed by ground, 84, 85, 86 of P^{12} , selector arm, 87, 88, resistance, battery and ground. P^{12} will respond, make busy the line 87 by immediate grounding at 89 and switch the winding 90 into circuit instead of its short-circuited winding 96, said winding 90 keeping P^{12} excited until the end of the connection. P^{12} further switches at 96 the line 91 over to 92 and after the levers of

the retarding relay V^{14} have fully fallen off J^{12} will be disconnected from line 94. If the subscriber's line be occupied P^{12} will not respond because either contact 88 is opened or line 87 is already grounded at another line selector.

Third—Second selection controlled from the office.

After through-connecting of the line 91 with 92 the call relay R^1 of the subscriber II will respond. R^1 will cause the adjustment of the call seeker AS^2 and the pre-selector VW^2 . The adjustment of both apparatus at first will be done in the same manner as described under the first part of this specification for the calling subscriber, i. e. the call seeker AS^2 adjusts itself and its test relay P^1 will start the pre-selector VW^2 by closing the contact 201. The difference exists solely therein that after adjustment of the call seeker in this case the retarding relay V^1 inserted over the line 92 will respond, while R^1 becomes deenergized. V^1 causes at 100 the reversing relay U^1 to respond, whereby the test relay P^2 will be switched over from the third upon the fourth pre-selector arm. For the understanding of this operation it is to be noted that the pre-selector is connected with two kinds of trunk lines, namely, lines leading to the multiple field for the calling subscribers (Fig. 4) and lines leading to the multiple field for called subscribers (Fig. 9). Of either kind of trunk lines about the same number is provided, but they are connected to the contact sets of the pre-selectors in a different manner in so far as the third strands are switched in one case upon the third and in another case upon the fourth contact arms. Therefore the pre-selector may test either upon the one or upon the other group of lines as desired and choose a free line according as to whether the test relay P^2 is connected either upon the third or upon the fourth selector arm. The switching over of the test relay P^2 upon the fourth arm, as effected in the arrangement of Fig. 8 by U^1 , will cause the pre-selector to adjust itself upon the supposed free line of Fig. 9. Hereby P^2 and C^1 will respond the same as before as P^1 is already excited. U^1 remains excited over 101 and 102 until the end of the connection in order to maintain the current for P^2 unchanged. V^1 will be switched off at 128 upon responding of C^1 and kept excited at 25 over VW^2 , 97, 98, J^{12} , battery and ground. J^{12} responds and switches at 102 the retarding relay V^{12} into circuit.

The relay J^3 in Fig. 6 which in adjusting the selector is continuously inserted into the impulse circuit closes at each rotation of the disk at the subscriber station I a circuit at 47 for the retarding relay V^2 . V^2

therefore after adjustment of the I. group selector will respond three times more and bring the controlling switch from position 3 into position 6. If the desired subscriber line is free J^s will remain excited in position 6 of the control switch, a circuit being formed over ground, battery, A¹, B¹, 1, 99, 92, LW, 96, 91, II.GW, 95, I.GW, 44, J^s , 41, S, 43, 42 and ground, as in the line selector 10 the impulse circuit will remain closed at 96. Now, the magnet S_t for the control switch will obtain an interrupting impulse over ground, 104, 105, position 6 of the arm 50, S_t , battery and ground. Hereby the 15 control levers will be brought into position 7.

Now, the numeral sender ZG will begin 20 its operation by sending current impulses over ground, 106, 52, D⁹, 107, battery and ground. The arm 108 will thereby be moved 25 forward in steps until it reaches the contact switched onto battery by the seeker arm 109. Thereupon the test relay P^s will respond and interrupt at 56 the current flowing over S_t , whereupon the control levers 30 will move into position 8. Now, D¹⁰ will receive current impulses which rotate the arm 110 until the arm 110 will find the contact switched by the seeker arm 109 onto battery and until the test relay P^s will 35 again respond. By this the current flowing over S_t will again be interrupted and consequently the control levers will be brought into the end position 9. Thereupon, as more 40 fully described below, the group selector and the line selectors, as well as the seeker and the numeral sender will be released or made free.

The number of the current impulses for 45 D⁹ and D¹⁰ is a different one for each position 50 of the seeker or for each branching point of the multiple field (Fig. 4). It depends upon the position of the seeker arms. As the 55 back selector is arranged for lifting and rotating, each branching point will be characterized by a two-ciphered number, and according to this also the contact field or the third seeker arm is formed.

The current impulses received from D⁹ and D¹⁰ will be transmitted by means of the 60 contacts 111 and 112 connected with these magnets upon the back selector over the control lever 55 after the relay J^s has been switched off by control lever 44. Each opening of the contacts 111 and 112 will cause the 65 relay J^{15} in Fig. 9 to be once deenergized, the circuit leading over ground, battery, J¹⁵, 98, 97, VW², 25, 93, AS², 99, 92, LW, 96, 91, II.GW, 95, I.GW, 55, 111 and ground. By closing 103 also V¹⁵ will be excited. The 70 first series of current impulses generated by repeated opening of contact 111 will now be transmitted at the back selector upon the lifting magnet H¹⁵ as follows: ground, battery H¹⁵, 116, 115, V¹⁵, 114, 113, 75 ground. V¹⁵, being retarding will remain

energized during the short intervals of the impulses but will be deenergized if the completion of the series of number impulses is followed by a larger interruption. At the first step of the selector RW contact 113 80 will close so that if after the completed series of current impulses V¹⁷ will be released, V¹⁶ will be excited over a circuit made by ground, 113, 114, 119, V¹⁶, 118, battery and ground. V¹⁶ by reversing of its 85 lever 116 will switch the rotating magnet D¹⁵ into circuit instead of the lifting magnet H¹⁵. The succeeding series of current impulses originating from 112 therefore will be transmitted to the rotating magnet D¹⁵, 90 V¹⁷ then again responding and closing contact 117, while 114 will open after the first step of rotation. After the last current impulse for rotation first V¹⁷ and somewhat later also V¹⁶ will be deenergized. In the 95 meanwhile the relay V¹⁸ will be switched into circuit over ground, battery, V¹⁸, 120, 121, 122, 113 and ground. V¹⁸ will hold itself over 123, 124 and switch the bell relay L at 125 upon a slow acting inter- 100 ruptor, whereby L will be excited in regular intervals and send alarm signals to the called subscriber. After completed adjustment of the back selector V¹ in Fig. 8 and J¹⁵ in Fig. 9 will be made inoperative, the 105 circuit for these relays being interrupted at the I. group selector at control lever 44 or 45. V¹ will extend the line at 93 to the subscriber II. J¹⁵ opens the contact 103, whereby the retarding relay V¹⁵ will be 100 made dependent on time contact Z''. The latter serves for releasing the back selector, if the called party does not answer after having received a certain number of alarm signals or after a certain number of excitations of the switching magnet D¹⁵.

If the subscriber called for now announces himself by taking off his receiver the supervisory relay U in Fig. 9 will respond and close the talking circuit which is shown by 110 heavily drawn lines at 126, 127 and will switch off the relay V¹⁸ at 124 and therewith also D¹⁵ and L. With U also J¹⁵ will respond and again maintain V¹⁵ independently 115 of the time contact Z'' for the entire duration of the conversation.

Fourth—Releasing the selectors.

The I. and II. group selectors, line selectors, seekers and numeral senders in Fig. 5 120 will immediately be made free after completed adjustment of the back selector. During motion of the control levers into position 9 J^s will be switched off at 44 and therefore made inoperative. Thereupon the 125 armature of P⁷ will also fall off with some retardation and close a circuit for the release magnet M^s at 129. Selector, control switch and numeral sender will be released together from M^s. The current for M^s will 130

be interrupted at 130 if the several apparatus will come into position of rest. The control lever 53 also interrupts the current for P^1 in Fig. 6, whereupon at 65 the release magnet M^{11} will be switched into circuit. M^{11} releases the second group selector. Similarly the line selector will be released by having the current for P^{12} interrupted by the back motion of the contact arms of the 10 second group selector. P^{12} will close at 131 the release circuit for M^{12} after J^{12} has already closed contact 132.

In a similar manner the release of the 15 group selectors, the line selectors and seekers is accomplished if in the line selector a subscriber line is found to be occupied. The control switch of the first group selector is at the respective instant in position 6. If hereby in the line selector the contact 96 of 20 the test relay P^{12} had not been closed, J^8 and also P^7 will remain inoperative. The further release will take place as just described.

Relay P^7 also will be automatically 25 switched off independently of the selecting operations by means of a time contact Z' , which may be made by a slow operating switch gear in case the calling subscriber be taking too much time in making connection.

If the calling subscriber hangs up the 30 receiver, J^1 in Fig. 4 will become inoperative, also V^7 and with some retardation also V^6 . In the meantime line 13 will also be interrupted at 14 and P^2 in Fig. 4 become inoperative. Upon P^2 C^1 will follow by reason 35 of the current being interrupted at 22, and upon C^1 will follow T^1 by reason of interruption of current at 27.

If the called subscriber, now, will hang up the receiver J^{15} U will become inoperative. 40 J^{15} switches off V^{15} at 103. The levers of V^{15} will fall back a little retarded, whereby contact 134 switches the release magnet M^{15} into circuit, while 136 will interrupt the current for P^2 in Fig. 8, here similarly to Fig. 3 45 the relays C^2 and T^1 will fall off and also U^1 hereby is switched off at 102 by C^2 .

Instead of arranging the multiple field A immediately behind the pre-selectors VW^1 , a group selector GW^1 Fig. 2 may be inserted 50 between said pre-selectors and the multiple field. In very large systems this selector is to be used to select the office to which the desired line is connected. The preliminary and its replacing talking circuit preferably extend only over the circuits of the office of the desired subscriber's line.

The insertion of the group selector GW^1 between the pre-selectors VW^1 and the relay set Fig. 4 does not change the arrangement 60 of either one of these sets, therefore the foregoing operations of establishing the preliminary and the talking connections with the desired line remain unchanged.

Having thus described my invention I

claim as new and desire to secure by Letters 65 Patent of the United States:—

1. A telephone exchange system, comprising subscribers' stations, subscribers' lines, trunk lines, selectors for establishing a preliminary connection between a calling station and a called station, a plurality of switches in series for establishing a talking connection replacing said preliminary connection, some of said switches being arranged for automatic selection some for selection by number impulses. 75

2. A telephone exchange system comprising subscribers' stations, subscribers' lines, trunk lines, selectors controlled by a calling station for establishing a preliminary connection between a calling station and a called station, a first multiple field with contacts less numerous than the number of subscribers' lines, a second similar multiple field, automatically operating switches for connecting a calling subscriber's line with said first multiple field, automatically operating switches for connecting a called subscriber's line with said second multiple field, switches for interconnecting the contacts of said multiple fields, and means for releasing said selectors of the preliminary connection. 80

3. A telephone exchange system comprising subscribers' stations, subscribers' lines, trunk lines, selectors controlled by a calling station for establishing a preliminary connection between a calling station and a called station, a first multiple field with contacts less numerous than the number of subscribers' lines, a second similar multiple field, 100 switches to interconnect the contacts of said multiple fields, automatically operating switches to connect a calling subscriber's line with said first multiple field, automatically operating switches to connect a called subscriber's line with said second multiple field, some of said automatically operating switches being used as well for calling as for called subscribers' lines, and means for releasing said selectors of the preliminary connection. 110

4. A telephone exchange system comprising subscribers' stations, subscribers' lines, trunk lines, selectors controlled by a calling station for establishing a preliminary connection between a calling and a called station, a first multiple field with contacts less numerous than the number of subscribers' lines, a second similar multiple field, switches for interconnecting the contacts of said multiple fields, a plurality of automatically operating switches for connecting a calling subscriber's line with said first multiple field, automatically operating switches to connect a called subscriber's line with said second multiple field, said selectors being branched off from the contacts of said first multiple field. 115

5. A telephone exchange system comprising

ing subscribers' stations, subscribers' lines, trunk lines, selectors controlled by a calling station, multiple fields with contacts less numerous than said subscribers' lines, automatically operating switches for connecting said subscribers' lines with said multiple fields, said selectors controlled by a calling

station being branched off from the contacts of one of said multiple fields and arranged 65
5 to establish a preliminary connection from said calling station to a desired station, switches for interconnecting the contacts of said multiple fields and establishing a talking connection between said subscribers' lines, and means for releasing said preliminary connection after establishing said talking connection.

6. A telephone exchange system, comprising subscribers' stations, subscribers' lines, trunk lines, automatically operating switches, a multiple field with contacts less numerous than said subscribers' lines, selectors controlled by a calling station being branched off from contacts of said multiple field for

20 establishing a preliminary connection between said calling station and a called station, said multiple field being connected to some contacts of said automatically operating switches, another multiple field with

25 contacts less numerous than said subscribers' lines, said second multiple field being connected to other contacts of said automatically operating switches and switches for establishing a talking connection between 30 said subscribers' stations, said second multiple field leading to said last named switches.

7. A telephone exchange system comprising subscribers' stations, subscribers' lines, trunk lines, automatically operating switches, selectors controlled by a calling

40 station for establishing a preliminary connection between said calling station and a desired station, multiple fields with contacts less numerous than said subscribers' lines, said automatically operating switches connecting said subscribers' lines when calling or

45 calling with said multiple fields, other switches for establishing a preliminary connection, partially including some of said automatically operating switches, between contacts of said multiple fields, another set

50 of switches for establishing a talking connection between said contacts of said multiple fields, an impulse generating device becoming associated with a contact of said multiple fields and generating impulses corresponding to the location of said contact it becomes associated with delivering its impulses over said preliminary connection to said switches for establishing the talking connection.

8. A telephone exchange system comprising subscribers' stations, subscribers' lines, automatically operating switches, multiple fields with contacts less numerous than said subscribers' lines, some of said automatically operating switches connecting a subscriber's line when calling with one of said

55 multiple fields, some others of said automatically operating switches connecting a subscriber's line when called with another of said multiple fields, selectors controlled by said calling line for establishing a preliminary connection with said called line, another set of switches for establishing a talking connection between said contacts of

60 said multiple fields, an impulse generating device becoming associated with the one of said contacts of said multiple fields connect-

ing fields for establishing a preliminary connection with a desired station, switches for establishing a talking connection between the contacts of said multiple fields, said talking connection releasing and replacing said preliminary connection.

9. A telephone exchange system comprising subscribers' stations, subscribers' lines, trunk lines, automatically operating switches, multiple fields with contacts less numerous than said subscribers' lines, said 70
75 automatically operating switches connecting said subscribers' lines when calling or called with said multiple fields, an impulse generating device associated with said contacts of said multiple fields and generating im-

70 pulses corresponding to the location of the said contacts it becomes associated with, other switches for establishing a talking connection between said contacts of said multiple fields, said switches for establishing 75

80 the talking connection being set by the impulses generated by said impulse generating device.

10. A telephone exchange system comprising subscribers' stations, subscribers' lines, trunk lines, automatically operating switches, multiple fields with contacts, less numerous than said subscribers' lines, said automatically operating switches connecting said subscribers' lines when calling or

85 called with said multiple fields, other switches for establishing a preliminary connection, partially including some of said automatically operating switches, between contacts of said multiple fields, another set

90 of switches for establishing a talking connection between said contacts of said multiple fields, an impulse generating device becoming associated with a contact of said multiple fields and generating impulses corresponding to the location of said contact it becomes associated with delivering its im-

95 pulses over said preliminary connection to said switches for establishing the talking connection.

11. A telephone exchange system comprising subscribers' stations, subscribers' lines, automatically operating switches, multiple fields with contacts less numerous than said subscribers' lines, some of said automatically operating switches connecting a subscriber's line when calling with one of said

100 multiple fields, some others of said automatically operating switches connecting a subscriber's line when called with another of said multiple fields, selectors controlled by said calling line for establishing a preliminary connection with said called line, another set of switches for establishing a talking connection between said contacts of

105 said multiple fields, an impulse generating device becoming associated with the one of said contacts of said multiple fields connect-

- ed to the calling line, generating impulses corresponding to said contact, delivering said impulses over said preliminary connection and over said automatically operating switches of the called subscriber's line to said set of switches for establishing a talking connection and setting same to said contact of the multiple field connected to the calling subscriber's line.
12. A telephone exchange system comprising subscribers' stations, subscribers' lines, trunk lines, two multiple fields with contacts less numerous than said subscribers' lines, two sets of automatically operating switches in series, the first set of said automatically operating switches connecting said subscribers' lines with the second set of said automatically operating switches, testing circuits in said second set for selecting a free contact of one of said multiple fields, selectors controlled by a calling subscriber's station to establish a preliminary connection of the contacts of said multiple field with the desired line, a circuit extending said preliminary connection through the first set of said automatically operating switches causing a change in the testing circuit of said second set of automatically operating switches and adapting it to select a free contact of the other of said multiple fields connected with switches for interconnecting the contacts of said two multiple fields.
13. A telephone exchange system comprising subscriber's stations, subscribers' lines, trunk lines, automatically operating switches, a first multiple field with contacts less numerous than said subscribers' lines, a second similar multiple field, said automatically operating switches connecting said subscribers' lines when calling with said first multiple field and when called with said second multiple field, a set of selectors to be adjusted by a calling subscriber's line, relays associated with the contacts of said first multiple field, said relays connecting said calling line with said set of selectors for establishing a preliminary connection with the desired subscriber's line, and means to connect the contacts of said multiple fields.
14. A telephone exchange system comprising subscribers' stations, subscribers' lines, trunk lines, multiple fields with contacts less numerous than said subscribers' lines, automatically operating switches connecting said subscribers' lines when calling or called with said multiple fields, selectors controlled by a calling station to establish a preliminary connection with the desired subscriber's line, a set of switches to establish a talking connection between the contacts of said multiple fields, an impulse generating device associated with said contacts of said multiple fields, said switches establishing said talking connection being controlled by impulses generated by said impulse generating device, said impulses being transmitted over said preliminary connection, said preliminary connection consisting of two leads and associated contact arms and operating relays.
15. A telephone exchange system comprising subscribers' stations, subscribers' lines, trunk lines, selectors controlled by a calling station for establishing a preliminary connection between a calling station and a called station, a first multiple field with contacts less numerous than the number of subscribers' lines, a second similar multiple field, automatically operating switches for connecting a calling subscriber's station with said first multiple field, automatically operating switches for connecting a called subscriber's line with said second multiple field, switches for interconnecting the contacts of said multiple fields, said switches and the corresponding trunk lines being arranged for control over two wires separately, and means for releasing said switches of the preliminary connection.
- In witness whereof I have hereunto set my signature in the presence of two subscribing witnesses.
- ADOLF FRANKE.
- Witnesses:
WOLDEMAR HAUPT,
HARRY L. WILSON.
